Primary Examiner — Catherine A Tuttle(74) *Attorney, Agent, or Firm* — Gardner Groff & Greenwald, P.C.(57) **CLAIM**

The ornamental design for a children's toy, substantially as shown and described.

DESCRIPTION

FIG. 1 is a top perspective view of a children's toy, embodying my new design;

FIG. 2 is a top view thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

Portions shown in broken lines are for illustrative purposes only and form no part of the claimed design.

1 Claim, 3 Drawing Sheets(56)
